CLAIM

The ornamental design for a foundation leg bracket for solar wire management, substantially as shown and described.

DESCRIPTION

FIG. 1 is a top right perspective view of a foundation leg bracket for solar wire management showing the claimed design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

Portions of the foundation leg bracket for solar wire management that are not shown form no part of the claimed design.

The dashed lines in the figures show portions of the foundation leg bracket for solar wire management that form no part of the claimed design.
